CLAIM

The ornamental design for a display device, as shown and described.

DESCRIPTION

The present application is related to U.S. Design patent application Ser. No. 29/663,723, filed concurrently herewith, the entire disclosure of which is incorporated herein by reference.

FIG. 1 is a perspective view of a display device showing our design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof; and,

FIG. 7 is a bottom plan view thereof.

In the drawings, the claimed design is defined by the shaded surfaces: broken lines immediately adjacent shaded surfaces represent boundaries of the claim and form no part thereof. All other broken lines and unshaded surfaces illustrate portions of the display device that form no part of the claimed design. The appearance of any portion of the article between the break lines forms no part of the claimed design.
